PROTECTOR MECHANISM FOR LOOMS

Application filed April 10, 1928. Serial No. 268,941.

This invention relates to improvements in the protector mechanism for looms and it is the general object of the invention to provide a simple device which will hold the detector finger resiliently against the shuttle binder when the shuttle is boxed and operate to remove the binder finger pressure when the shuttle is being picked.

In the usual loom employing a fly shuttle the picking mechanism operates to propel the shuttle when the lay has reached approximately its mid position on its backward stroke. As ordinarily constructed the protector mechanism has a binder finger which is held under spring tension against the shuttle binder at all times. It is an important object of my present invention to provide a spring which will hold the finger against the binder during a portion of the cycle of the pick of the loom but effective to remove the spring pressure at the time of picking so that less power will be required to move the shuttle.

A shuttle will usually enter its shuttle box when the lay is approximately at its mid point when moving forwardly and it is therefore necessary at this time to have the protector mechanism operative to stop the loom should the shuttle fail to box properly. The lay is ordinarily actuated by a crank connector which is in relatively low position when the lay is moving forwardly and in relatively high position when the lay is moving rearwardly. It is a further object of my present invention to provide a connection between the crank which rises and falls as the lay moves to disable the spring during the backward movement of the lay, but to permit the same to be operative with respect to the protector finger on the forward movement of the lay so that protection may take place in the usual manner.

It is a more particular object of my present invention to provide a spring plunger surrounded by a compression spring, the plunger to operate prior to boxing of the shuttle to exert pressure against the binder by the protector finger, and said plunger being removed by the connection with the crank to lessen or entirely remove pressure against the binder

due to the protector finger when the lay is in picking position.

With these and other objects in view which will appear as the description proceeds, my invention resides in the combination and arrangement of parts hereinafter described and set forth in the claims.

In the accompanying drawings, wherein I have shown a convenient embodiment of my invention,

Fig. 1 is a front elevation of a portion of a lay having my invention applied thereto,

Fig. 2 is a vertical section on line 2—2 of Fig. 1 showing a portion of the breast beam in section and showing the lay in the position it assumes when moving forwardly, and

Fig. 3 is a view similar to Fig. 2 with the breast beam and loom parts omitted and with the lay and associated parts moving rearwardly or toward picking position.

Referring to the drawings, I have shown a loom frame 10 having a breast beam 11 on which may be mounted knock-off mechanism 12. Said mechanism may cooperate with a dagger 13 carried on a protector rod 14 which is oscillatable in a bracket 15 secured to the lay 16. The lay may be supported by swords, one of which is indicated at 17, and may have a pair of shuttle boxes 18 which rise and fall so that first one and then the other of the shuttles S is moved into active position with respect to the race plate 19 on the lay. Each shuttle box is provided with a binder 20 which is moved outwardly or toward the breast beam by the shuttles when they are boxed.

The binder corresponding to the active shuttle is adapted for cooperation with a protector finger 21 which is secured to the protector rod 14 in fixed angular relation with respect to the dagger 13. Connector rods 22, of which there are two, have connection as at 23 with the lay and are driven by any means such as the top or crank shaft of the loom not shown to move the lay backwardly and forwardly away from and toward the breast beam 11.

In normal operation the shuttle which is active will move back and forth across the lay, starting its flight by mechanism not shown when the lay is moving backwardly

and in the position shown in Fig. 2, and completing its flight when the lay is moving forwardly and in substantially the position shown in Fig. 3. When the shuttle is properly boxed the corresponding binder 20 will move the protector finger 21 forwardly or into the full line position shown in Fig. 2, the effect of which is to depress the dagger 13 so that the same will move forwardly without engagement of the knock-off mechanism 12. Should the shuttle fail to be boxed, however, the binder corresponding to the active shuttle box will not be moved forwardly and the finger and dagger will assume the position shown in dotted lines in Fig. 2, the dagger engaging the knock-off device 12 to effect immediate stoppage of the loom to prevent breakage of the warp threads. The mechanism thus described is of common construction and forms no part of my present invention.

In carrying my improvements into effect I provide means whereby the binder finger 21 will be moved yieldingly toward the shuttle binder corresponding to the active shuttle during the forward movement of the lay and I provide further for moving the protector finger away from the binder during the backward stroke of the lay. This result I achieve by providing a depending arm 30 having a hub 31 which is held in fixed but adjustable angular position on the protector rod 14 by a set screw 32. Pivottally connected to said arm at the lower end thereof as at 33 is a rearwardly extending spring rod or plunger 34 having on the forward end thereof a collar 35 which is adjustable along the rod and is retained in adjusted position by set screw 36.

Surrounding the rear portion of the rod behind the collar 35 is a compression spring 37, the rear end of which engages a clip 38 secured to the underside of the connector rod 22 by means of bolts 39. The plunger 34 extends through an opening 40 in the clip and has the rear end thereof threaded as at 41 to receive a pair of nuts 42 adjustable along the rod and acting to engage the rear surface of the clip 38 to limit forward movement of the plunger 34 under action of the spring 37.

In operation, it will be understood that the connector 22 will assume two angular positions with respect to the lay when the latter is substantially midway between its extreme forward and backward positions and that said connector will be inclined downwardly and rearwardly as indicated in Fig. 2 when the lay is moved forwardly as suggested by arrow A, Fig. 2, and that said connector 60 will be inclined upwardly and rearwardly when the lay is moving rearwardly as suggested by arrow B in Fig. 3. The connector rod will ordinarily move in a vertical plane which is perpendicular to the lay. The depending portion of the clip 38 will therefore

be in two different angular positions when the lay is in its mid position, depending upon the direction of movement of the lay. When the lay is advancing the clip will be in the relatively forward position to compress spring 37 and through the latter urge the protector finger 21 against the shuttle binder corresponding to the active shuttle. The finger is therefore held at this time in position to be controlled by the binder so that the dagger 75 may receive its normal movement away from the knock-off device 12 if the shuttle is properly boxed.

On the backward stroke of the lay, however, the clip 38 will be moving relatively 80 rearwardly as indicated in Fig. 3 and will engage the nuts 42 so as to move the arm 30 rearwardly and thereby rock the protector rod 14 in a clockwise direction as viewed in Fig. 3 to move the protector finger 21 out of 85 engagement with the binder corresponding to the active shuttle. The latter may therefore be picked with less power than would be the case if the pressure of spring 37 were permitted to bear against the shuttle. By varying the position of the nuts 42 along the rear end of the plunger or rod 34 the time and also the degree of movement of the protector finger 21 may be changed.

From the foregoing it will be seen that I 95 have provided a very simple means for permitting a spring to exert its pressure against a protector finger during the boxing of the shuttle to permit the usual protecting operation, and that said binder finger is moved to 100 pressure relieving position at the time of picking. It will also be seen that the parts operate with the use of a single spring which at times is ineffective to exert pressure on the binder finger and at other times is compressed 105 by the clip 38 to exert pressure against the binder. By the arrangement set forth herein I find it unnecessary to employ the difficultly replaceable usual torsion spring customarily placed around the protector rod 14.

Having thus described my invention it will be apparent that changes and modifications may be made therein by those skilled in the art without departing from the spirit and scope of the invention and I do not wish to be limited to the details herein disclosed, but what I claim is:

1. In protector mechanism for a loom having a lay to move backwardly and forwardly and a shuttle normally to be boxed when the lay is moving in one direction and to be picked when the lay is moving in the other direction, a lay driving crank connector movable relatively to the lay in a plane substantially perpendicular to the lay, said connector moving in one direction relatively to the lay immediately prior to boxing of the shuttle and movable in another direction relatively to the lay immediately prior to picking, a protector finger capable of resisting movement 130

of the shuttle, a depending arm fixed with respect to the protector finger and movable with the latter, a rod pivotally connected to said depending arm and extending rearwardly, a spring surrounding said rod, and supporting means for the rear end of the rod through which the latter extends, said supporting means being carried by the crank connector and effective when the shuttle is being boxed to compress the spring and effective when the shuttle is being picked to move the rod to move the finger to shuttle relieving position.

2. In protector mechanism for a loom having a lay to move backwardly and forwardly and a shuttle normally to be boxed when the lay is moving in one direction and to be picked when the lay is moving in the other direction, a lay driving crank connector movable relatively to the lay in a plane substantially perpendicular to the lay, said connector moving in one direction relatively to the lay immediately prior to boxing of the shuttle and movable in another direction relatively to the lay immediately prior to picking, a protector finger capable of resisting movement of the shuttle, a rod operatively connected to the finger and movable with the latter, a spring surrounding the rod, and spring engaging means carried by the crank connector, said means effective when the shuttle is being boxed to engage the spring and through the latter transmit yielding pressure to the finger to resist movement of the shuttle, and said means movable when the shuttle is being picked to engage the rod to relieve the pressure of the spring and thereby diminish the resistance offered by the protector finger to the movement of the shuttle.

3. In protector mechanism for a loom having a lay to move backwardly and forwardly and a shuttle normally to be boxed when the lay is moving in one direction and to be picked when the lay is moving in the other direction, a lay driving crank connector movable relatively to the lay in a plane substantially perpendicular to the lay, said connector moving in one direction relatively to the lay immediately prior to boxing of the shuttle and movable in another direction relatively to the lay immediately prior to picking, a protector finger capable of resisting movement of the shuttle, a depending arm movable in fixed angular relation with respect to the protector finger, a rearwardly extending rod pivotally connected to said arm, a spring surrounding said rod, supporting means for the rear end of the rod carried by the crank connector and movable with the latter, said supporting means engaging the spring to compress the latter to cause the same to exert yielding pressure against the binder finger when the shuttle is being boxed, and said supporting means positively engaging and withdrawing the rod and thereby

moving the protector finger to a position to relieve resistance to the motion of the shuttle when the latter is being picked.

4. In protector mechanism for a loom having a lay to move backwardly and forwardly and a shuttle normally to be boxed when the lay is moving in one direction and to be picked when the lay is moving in the other direction, a lay driving crank connector movable relatively to the lay in a plane substantially perpendicular to the lay, said connector moving in one direction relatively to the lay immediately prior to boxing of the shuttle and movable in another direction relatively to the lay immediately prior to picking, a protector finger capable of resisting movement of the shuttle, a depending arm movable in fixed angular relation with the detector finger, a rearwardly extending rod pivotally connected to the depending arm, a collar fixed to and movable along the rod toward and from the pivotal connection between the rod and the depending arm, supporting means carried by and moving with the crank arm for the rod and through which said rod extends, a compression spring surrounding the rod and located between the collar and said supporting means, and a member located on the rod behind the supporting means to be engaged by the latter, said supporting means compressing the spring to increase the resistance which the protector finger offers to the movement of the shuttle when the latter is being boxed, and said supporting means engaging the member therebehind on the rod to move said detector finger to shuttle relieving position when the shuttle is being picked.

In testimony whereof I have hereunto affixed my signature.
